UNITED STATES PATENT OFFICE.

JOAH BROGDEN, OF MELROSE PARK, PENNSYLVANIA.

VISE.

Application filed August 17, 1925. Serial No. 50,677.

This invention relates to vises of the kind used by mechanics to hold work upon which they are engaged; and it has more particular reference to that type commonly known 5 as "field" vises in contra-distinction to the heavy or bench varieties. The main object is to facilitate manipulation of such vises by obviating the tedious turning of the actuating screws when initially spacing the 10 clamping jaws to accommodate articles of different widths as is ordinarily necessary with standard designs of such character heretofore prevalent.

One way in which the foregoing desideratum—together with other objects and practical advantages—may be conveniently attained, will be manifest from the detailed description hereinafter of the typical embodiment of my invention shown by the 20 drawings, whereof Fig. I is a plan view;

Fig. II is a side elevation of the vise with portions broken away to disclose important details of construction; and,

Fig. III is a cross section of the structure 25 taken as indicated by the arrows III—III in Fig. I.

As depicted, my improved vise comprises a flat elongated base 5 with an upstanding projection 6 at one end which serves as the 30 fixed clamping jaw, and a smaller upstanding abutment projection 7 at the other end for a purpose to be later explained, said projections 6—7 being preferably formed integral with the base as illustrated. Mov- 35 able in the interval between the fixed jaw 6 and the abutment 7, is an opposing clamp jaw 8 having the form of a block with a tongue 9 that depends into a guideway 10 cut or otherwise formed in—and extending 40 longitudinally of—the base 5. The movable jaw 8 is held in the assembly by a keeper plate 11 which is secured to the tongue 9 by screws 12, and engages a recess 13 extending medially along the bottom of the base 5 be- 45 neath the slot 10 aforesaid. The movable jaw block 8 is made hollow as indicated at 14 to receive a head 15 at one end of the vise actuating screw designated 16, said end terminating in a reduced portion 17 that is 50 freely revolvable in the head and prevented from axial displacement by a cap screw 18. A pin 19 extending continuously through the side walls 20 of the movable jaw block 8 at a point above the reduced portion of

the actuating screw 16, provides a fulcrum 55 axis eccentric from its longitudinal axis and about which the actuating screw 16 may be swung for quick engagement and release relative to a cooperating threaded notch 21 centrally of the abutment 7 previously referred to. More particularly from Fig. II, it will be observed that the top of the abutment 7 is declined with respect to the actuating screw while the threaded notch 21 surrounds the lower half of said screw at 21^a so 60 as to facilitate the operation just explained. The actuating screw 16 being eccentrically pivoted in the movable jaw 8 and the threaded notch 7 being inclined towards the jaw, it is apparent that the axial thrust attending 65 rotation of the screw 16 is resolved downward and rearward thus maintaining the screw against normal dislodgement from the threaded abutment. At its outer end the actuating screw 16 has an enlargement 70 75 75 which is pierced to receive the grasp rod 24 with sufficient clearance for free endwise sliding in a manner characteristic of ordinary vise construction.

In operation it will be apparent that by 80 lifting the actuating screw from engagement with the cooperating thread 21 in the abutment 7—as shown in dotted lines in Fig. II, the clamping jaw 8 may be shifted quickly to roughly adjust the same relative 85 to the fixed jaw 6 in accordance with the width of the article to be clamped. After the movable clamping jaw 8 is thus approxi- 90 mately set at the desired distance from the fixed jaw 6, the actuating screw 16 is replaced within the cooperating threaded notch 21 and said screw turned to clamp the article, the slope 21^a of the abutment 7 serv- 95 ing at this time to oppose axial thrust of the actuating screw 16 and hold it against displacement from said cooperating notch 21.

Having thus described my invention, I claim:

1. In a vise of the character described, the combination of a base, a stationary clamp jaw and a screw threaded abutment integral with said base, an opposing clamp jaw mov- 100 able in the interval between said stationary jaw and abutment, and an actuating screw pivoted in the movable jaw and normally seated in—and half-surrounded by—the threaded abutment, whereby said screw is held substantially parallel to the plane of 105

the base, the axis of said pivot being offset relative to the axis of rotation of the actuating screw.

2. In a vise of the character described, the combination of a base, a stationary clamp jaw and a fixed abutment integral with said base, an opposing clamp jaw movable in the interval between said stationary jaw and abutment, and an actuating screw pivoted in the movable jaw, said abutment having a screw threaded notch normally surrounding—and engaging with—the lower longitudinal half of the actuating screw, whereby the screw is retained against dislodgment under axial thrust attending its rotation.

3. In a vise of the character described, the combination of an elongated base having an integral clamp jaw at one end and a threaded abutment projection at the other end, a relatively-movable opposing clamp jaw, an actuating screw normally engaged in—and half-surrounded by—the threaded abutment whereby said screw is retained substantially parallel to the plane of the base, and a head wherein one end of the actuating screw is revolvably retained, said head being eccentrically pivoted to the movable clamp jaw for quick engagement and release of the actuating screw relative to the threaded abutment projection aforesaid.

4. In a vise of the character described, the combination of a base, a stationary clamp jaw and a threaded abutment in spaced relation and integral with said base, an opposing clamp jaw movable in the interval between said stationary jaw and abutment, and an actuating screw eccentrically hinged at its inner end to the movable clamp jaw for quick engagement and release relative to the threaded notch in the abutment aforesaid, said actuating screw being normally seated

in—and half-surrounded by—the threaded notch, whereby it is held in a substantially horizontal position.

5. In a vise of the character described, the combination of an elongated base having an integral clamp jaw at one end and a screw threaded notched projection at the other end, a relatively-movable opposing clamp jaw, and an actuating screw rotatably hinged at its inner end in the movable clamp jaw aforesaid for quick engagement and release relative to the threaded notch projection, said notch being declined with respect to the actuating screw and normally half-surrounding—and engaging with—said screw whereby the screw is retained in substantially parallel relation with the plane of the base so as to facilitate engagement and release of the same and to better retain it against dislodgment from the cooperative threaded notch under axial thrust attending operative rotation of said screw.

6. A field vise comprising a base having a stationary jaw at one end and a threaded notch-abutment at the other end, an opposing clamp jaw movable in the interval between said stationary jaw and abutment, and an actuating screw fulcrumed at the inner end above its sphere of axial rotation in the clamp jaw and co-operative with respect to its lower longitudinal half in the threaded notch-abutment, whereby the opposing thrust of the movable jaw is resolved downward and rearward for positive maintenance of the actuating screw against dislodgment from the threaded notch in the abutment aforesaid.

In testimony whereof I have hereunto signed my name, at Philadelphia, Pa., this fourteenth day of August, 1925.

JOAH BROGDEN.
